OIL WELL PUMPING TRANSMISSION

Charles G. Boone, Tulsa, Okla., assignor to Gus-tin-Bacon Manufacturing Co., Kansas City, Mo., a corporation of Missouri

Application June 17, 1937, Serial No. 148,697

5 Claims. (Cl. 74—593)

My invention relates to an oil well pumping transmission and more particularly to a transmission for reciprocating movement in which means are provided for controlling the duration 5 of the transmission of power.

While my invention will be described with respect to its application to oil well pumping, it is to be understood that it is of general application in transmitting reciprocating motion.

10 Currently, it is the practice in removing petroleum from wells to employ a reciprocating single acting pump operated by a line of rods called "pull rods". After a well has been in production for a period of time, gas pressure present in the 15 pool, which normally forces the oil to the surface, causing it to flow, is depleted so that pumping must be resorted to remove the oil from the well. On shallow production, it is customary to erect a large power driven band wheel on a lease from which a plurality of wells are pumped. The 20 band wheel is driven by a gasoline engine or an electric motor or any other suitable prime mover and is provided with one or more eccentrics having radially extending arms running to rod lines 25 through which the various pumps of the respective wells are operated. Some wells employ a "front" in which a motor is used to reciprocate a walking beam to one end of which is attached the line of sucker rods.

30 At some time in the life of an oil well, the amount of oil flowing to the well becomes so small that the well cannot be pumped continuously. When the supply of oil to the suction of the pump is depleted, the pumping equipment 35 will "pound down". Pumping an empty well, that is, when no load is imposed upon the sucker rods during their upstroke, imposes severe strains on the rod line and very frequently causes its rupture. Valve seats and other pumping equipment 40 are subjected to severe strains, frequently resulting in their injury. To avoid "pounding down" the pumping equipment is usually disconnected. In such case, the pull rod line is supported by a post adapted to support the weight 45 of the sucker rod string, called the "knock-off post". The rod line is supported by the knock-off post and the well is allowed to "rest" until oil has accumulated. When sufficient oil has accumulated 50 in a well, depending upon the speed with which oil will flow from the formation into the well, the rod line is again connected to the pumping equipment. The manual connecting and disconnecting of the rod line to the pumping equipment entails considerable work and involves 55 inconvenience. Unless the pumping is discon-

nected before the supply of oil in the well is depleted, pounding down will occur. The strain of connecting the sucker rods to the power introduces stresses which sometimes breaks the rod line. This manner of operating is common and a well may be "on the pump" for various periods daily.

When a well is "knocked off", oil from the formation flows into the well. When the liquid level in the well rises to a point such that its hydrostatic 10 pressure equals the pressure existing in the formation, no further oil will flow into the well. If, however, the oil could be removed from the well at a rate equal to its flow into the well so that a hydrostatic head equal to the pressure forcing 15 the oil into the well is never reached, a continuous flow of oil could be achieved. Present pumping equipment is such that it cannot be operated below a predetermined velocity of motion due to leakage past cups and valves. This leakage is 20 called "slippage". The result is that, in order to pump at all, the velocity of the pump stroke must be at a predetermined minimum.

One object of my invention is to provide a method of pumping oil from the oil wells at a mean 25 effective rate equal to the rate of flow of oil into the well.

Another object of my invention is to provide means for operating pumping equipment at a predetermined velocity intermittently so that the 30 mean effective velocity of the pumping stroke or the average velocity over a period of time will be approximately equal to the rate of flow of oil into the well, while the velocity of any one stroke 35 will be sufficiently high to enable oil to be pumped efficiently.

Another object of my invention is to provide an oil well pumping transmission interposed between the power and the pump whereby the pump is operated intermittently with short rest periods 40 in between in which pumping periods and resting periods are automatically varied as a function of time.

Another object of my invention is to provide a transmission which automatically connects the 45 power and disconnects it in predetermined phase relation to the number of pumping strokes.

Other and further objects of my invention will appear from the following description.

In the accompanying drawings which form part 50 of the instant specification and are to be read in conjunction therewith and in which like reference numerals are used to indicate like parts in the various views;

Figure 1 is a perspective view of a transmission 55

embodying one mode of carrying out my invention and adapted for use in my method of oil well pumping.

Figure 2 is a plan view with parts broken away, 5 of the transmission shown in Figure 1.

Figure 3 is a sectional view taken on the line 3-3 of Figure 2.

Figure 4 is a sectional view taken on the line 4-4 of Figure 2.

Figure 5 is a sectional view taken on the line 5-5 of Figure 4.

In general, my invention contemplates interposing between a reciprocating driving means and a driven means, a transmission adapted to 15 form a connection between the driving and driven means in which the reciprocating driving means operates a connecting means adapted to connect the reciprocating driving means and the driven means in response to a predetermined 20 number of reciprocations of the driving means and in which means are provided for disconnecting the reciprocating driving means from the driven means in response to a predetermined 25 number of reciprocations of the driven means.

More particularly referring now to the drawings, the reciprocating driving means is shown 30 as a link 1 secured to driving head 50, to which is secured by means of bolts 51, a channel 2. The link 1 is adapted to be given a reciprocating motion by an eccentric, cam, or crank driven by any suitable prime mover (not shown). The channel 2 is adapted to be reciprocated on guide flanges 3 of members 4, as can readily be seen by reference to Figure 4. The members 4 are secured 35 by stud bolts 5 to a pair of frame members 6. Members 4 are held in predetermined spaced relation by through bolts 7 and provided with spacing bushings 8. Secured to frame members 6 by means of bolts 67, is a goose-neck 40 9 adapted to fit a knock-off post 10. The end 12 of the rod line 11 passes through the slot 13 in the knock-off post 10 and is secured to the goose-neck 9 by means of a clamping plate 14 and stud bolts 15 as can readily be seen by reference 45 to Figure 3. The end of the rod line 12 may be upset to form a rivet head 16. Secured to driving channel 2 by means of stud bolts 17 is a plate 18. Mounted upon plate 18 and secured thereto and to the driving channel is a 50 stop or detent plate 19. Extending between members 4 is a shaft 20 upon which is pivoted a pawl 21. A squared bar 22 extends between members 4. Secured to bar 22 by stud bolts 23 is a flexible metallic leaf 24. Members 4 are 55 provided with lugs 25 formed with reentrant portions 26 to form a well in which is seated a spring 28. The upper end of the spring engages the under side of leaf 24. A shaft 27 is journaled in suitable bearings in members 4. Keyed to shaft 60 27 by key 29 is a cam 30 against which spring 28 forces one end of leaf 24. The pawl 21 is secured to leaf 24 by means of bolt 31 and spring 32. The spring 32 allows resilient relative motion of 65 the pawl and the leaf 24. The nut 33 governs the compression of the spring 32. Members 4 are provided with a sheathing 34 secured to the edges of members 4 by means of bolts 35, the sheathing 34 and the members 4 forming a 70 housing.

Suitable bushings 36 may be provided in members 4 to form bearings for the shaft 27. Keyed to shaft 27 by keys 37 are internal members 38 of overrunning clutches. The housings 39 of the overrunning clutches are pivoted upon shaft 27 75 and held in assembled position by means of nuts

40 as can readily be seen by reference to Figure 4. The overrunning clutch construction may be of any suitable type in which gripping rollers 41, shown in Figure 5, are adapted to jam the housing 39 to internal clutch member 38 when the 5 housing moves in a counterclockwise direction relative to the internal clutch member. The housing members 39 are provided with upper lugs 42 to which arms 43 are secured by bolts 44. The arms 43 are provided with weights 45, adjustably secured thereto by set screws 46. The weights acting through the arms tend to rotate the housings 39 in a clockwise direction which movement is readily permitted as the gripping rollers 41 will move to non-gripping position. 15

The housings 39 are also provided with lower lugs 47 adapted to engage stop pins 48 secured to the members 4 to limit the clockwise motion of the housings under the influence of the weights 45. Secured to the driving head 50 by 20 means of bolts 52 is a bracket 53 which adjustably supports a push rod 54. The push rod may be adjusted longitudinally of its axis in the bracket 53 and is held in adjusted position by a set screw 55. Secured to the exterior of one of 25 said housings 39 by means of bolts 56 is an angle 57. The angle 57 is secured below the center of the housing. The push rod 54, upon reciprocation relative to the housing, is adapted to strike the angle 57 and rotate the housing counterclockwise, thus causing it to rotate member 38 which is keyed to the shaft 27, causing it to 30 rotate.

Link 58 is pivotally secured to goose-neck 9 by means of stud bolt 59. Secured to the outer end 35 of link 58 is a push rod 60 which is supported near its other end by a bracket 61, secured to one of the side members 6 by means of bolts 62. The end of push rod 60 is adjacent an angle flange 63 which is secured to one of the housings 39 by means of bolts 64. Movement of the push rod 60 to the left, as viewed in Figure 1, will cause it to strike angle 63, rotating the housing 39 in a counterclockwise direction. Movement of the housing 39 in a counterclockwise direction will cause rollers 41 to grip and transmit movement of the housing 39 to the member 38 of the clutch. Member 38 is keyed to the shaft 27 so that movement of the housing 39 counterclockwise will cause the shaft 27 to 50 rotate counterclockwise. 40

The link 58 is adapted to swing over the open portion of the goose-neck 9 which normally embraces the knock-off post 10. Engagement of the link 58 with the knock-off post will cause it to 55 pivot, moving the rod 60 to the left as viewed in Figure 1. The amplitude of this motion is governed by the position of rod 60 in the block 65. Rod 60 may be adjusted longitudinally in block 65 which is carried by the end of link 58 and 60 held in adjusted position by means of set screw 66.

In operation, assuming the position of parts shown in Figure 3, the weight of the sucker rods is being carried by the knock-off post 10 through 65 the goose-neck 9, and the reciprocating member 1, driving head 50 and channel 2 are reciprocating idly without transmitting the reciprocating motion to the pumping string. The frame members 6, members 4, and associated parts are stationary. Upon each reciprocation, the push rod 54 carried by the bracket 53 strikes the angle 57 secured to the lower portion of housing 39, rotating it in a counterclockwise direction. The amplitude of counterclockwise rotation is governed 70 75

5 by the position of push rod 54. It will be obvious by reference to Figure 2, that as the push rod 54 is moved to the right, as viewed in that figure, it will contact angle 57 and move it to the right, thus rotating the housing to which angle 57 is attached. Rotation of the housing 39 counter-clockwise will rotate member 38 counterclockwise, rotating the shaft 27 to which it is keyed, and rotate cam 30, which is keyed to shaft 27. It

10 will be obvious that every time the push rod 54 strikes angle 57 and moves it, that cam 30 will move in a counterclockwise direction, depending upon the amplitude of motion which is governed by the adjustment of push rod 54 on bracket 43.

15 The rotation of housing 39 in a counterclockwise direction is against the action of the weight 45. When driving head 50 moves to the left, the push rod will move away from the angle 57 and permit the weight 45 to rotate the housing in a clockwise direction until the lug 47 engages the stop 48.

20 Since the prime mover is driven at a constant speed and the movement of the cam 30 varies directly as a function of the number of reciprocations, it will be obvious that the adjustment of push rod 54 will control the movement of cam 30 as a function of time and as a function of the number of reciprocations of the driving head 50.

25 By reference to Figure 2, it will be observed that, as the cam 30 rotates, it will depress the leaf 24 against the action of spring 28. As the leaf 24 is depressed, the pawl 21 is lowered. The action will continue until the toe 69 of the pawl engages the edge 70 of the stop member 19. The edge 70 of the stop member 19 is slightly beveled to maintain the pawl and stop member in engaged position when a load is being carried. The parts are shown in Figure 2 at the limit of the reciprocating motion. The arrangement is such that engagement is always made at the limit of reciprocating motion which is the point of least acceleration so that, as a load is taken, a minimum strain is interposed upon the line of sucker rods, the strain being no more than is normally imposed during the pumping of the well. When pawl 21 engages stop plate 19, the prime mover is operatively connected to the rod line through the following linkage: prime mover, link 1, driving head 50, channel 2, stop plate 19, pawl 21, shaft 20, members 4, frame member 6, goose-neck 9, rod line 11. The reciprocation of the driving head will now be imparted to the rod line and the well will be pumped through the operation of the pump through the rod line, as is well known to the art. When member 58 reciprocates with members 4, there will be no relative motion between push rod 54 and angle flange 57 and, if no other means were provided, the pumping would continue indefinitely, as long as the prime mover operated. It will be observed that link 58 is now reciprocated with respect to the knock-off post 10, since it is carried by the goose-neck which is being reciprocated.

30 The adjustment of push rod 60 is such that the angle plate 63 normally engages the end of the rod, and, through the influence of weight 45, will hold the rod sufficiently to the right so that the link 58 will be in a position partially across the open end of the goose-neck. In this manner, upon reciprocation, the link 58 will strike the knock-off post 10, rotating the link around its pivot in a counterclockwise direction, moving push rod 60 to the left, causing it to rotate housing 39 in a counterclockwise direction through angle plate 63. The amplitude of motion, as will be readily understood, is controlled by the position of push rod 60. Counterclockwise rotation of the

35 housing 39 will rotate the shaft 27 in a counterclockwise direction through the overrunning clutch assembly, thus causing the cam 30 to continue to rotate in a counterclockwise direction. As this occurs, the leaf 24 will be moved upwardly under the influence of spring 28, thus compressing the spring 32. When the load is momentarily off the pawl at the extreme limit of the stroke, that is, when the goose-neck bears against the knock-off post and the load is thus momentarily carried by the knock-off post, the spring 32 will lift the pawl from engagement with the detent so that, upon the return stroke, no pumping will occur, the linkage between the driving and the driven means being thus broken. It will be observed that the arrangement is such that the disconnecting of the driving means from the driven means occurs at the limit of the stroke and thus without shock.

40 The adjustment of push rod 54 will determine the length of time that the driving means is disconnected from the driven means, while the adjustment of push rod 60 will determine the length of time the driving means is connected to the driven means. In this manner, I have provided a very flexible transmission. I may have the pump operate for one stroke and remain idle any number of strokes. I may have the pump operate for any number of strokes and then remain idle for any number of strokes, depending upon the adjustment of the respective push rods 54 and 60. I am thus enabled to obtain any desired mean effective pumping rate, while enabling the prime mover to run at a constant speed and the pumping assembly to operate at an efficient speed.

45 It will be readily observed that I have accomplished the objects of my invention. By means of my transmission, I am enabled to pump a well at a rate substantially equal to its rate of flow and thus prevent the building up of a hydrostatic head of oil within the well which would prevent further flow of oil into the well. The constant flow of oil will maintain the porosity of the formation. I have found that, by intermittent operation, sediment carried from the formation through the channels naturally present in the formation, tends to reduce the porosity thereof and hence further reduces the rate of flow of oil into the well. Pounding down, with consequent possible injury to the pumping equipment and sucker rod strain is avoided. The labor, inconvenience, and danger of connecting and disconnecting the pumping string from the power is avoided. Increased recovery of oil from the well is obtained. By means of my method, I have been enabled to more than double the daily production of a well which could not be constantly pumped at the lowest rate possible with the pumping equipment.

50 It will be understood that certain features and subcombinations are of utility and may be employed without reference to other features and sub-combinations. This is contemplated by and is within the scope of my claims. It is further obvious that various changes may be made in details within the scope of my claims without departing from the spirit of my invention. It is, therefore, to be understood that my invention is not to be limited to the specific details shown and described.

55 Having thus described my invention, what I claim is:

60 1. In a pumping assembly having a driven reciprocating means positioned between a prime mover and a pump, said means adapted to trans-

- mit energy from the prime mover to the pump for actuating the same, a connector comprising a driving reciprocating member and a driven reciprocating part, said driven reciprocating part being carried by said driven reciprocating means, means for connecting said driving member to said driven part, means operated by the relative movement of said driving member with respect to said driven part for actuating said connecting means to connect said driving member to the driven part, and means actuated by the reciprocation of said driven part for actuating said connecting means to disconnect said driving member from said driven part.
- 15 2. In a transmission for reciprocating motion including in combination a constantly operating prime mover, a driving member connected to said prime mover for constant reciprocation, a driven part adapted to be intermittently connected to said driving member for transmitting the reciprocating motion, a connecting means for connecting said driving member to said driven part, means actuated as a function of the number of reciprocations of said driving member for operating said connecting means, and means operated as a function of the number of reciprocations of said driven part for operating said connecting means to disconnect said driving member from said driven part.
- 20 3. In a transmission for transmitting reciprocating motion, a constantly reciprocating driv-

ing member, a driven part with respect to which said driving member reciprocates, a stop on said driving member, a pawl on said driven part, means for operating said pawl to move it into and out of engagement with said stop, a pair of overrunning clutches for operating said pawl operating means, means operated by the relative motion of said constantly reciprocating driving member with respect to said driven part for actuating one of said overrunning clutches for moving said pawl into engagement with said stop, and means operated by the reciprocation of said driven part when it is connected to said driving member for operating the other of said overrunning clutches for disconnecting said pawl from said stop.

25 4. In a transmission as in claim 3 in which said means for operating said overrunning clutches are provided with adjusting means to control the extent of respective operations thereof.

5. In a transmission for transmitting reciprocating motion a constantly reciprocating driving member, an intermittently reciprocating driven part, means for connecting said driving member to said driven part in response to a predetermined number of reciprocations of said driving member relative to said driven part, and means for disconnecting said driving member from said driven part in response to a predetermined number of reciprocations of said driven part.

CHARLES G. BOONE.
